UNITED STATES PATENT OFFICE.

EDDY T. MCKAIG, OF CHICAGO, ILLINOIS, ASSIGNOR, BY MESNE ASSIGNMENTS, TO THE WHEELER COMPANY, A CORPORATION OF ILLINOIS.

CAR-SEAT.

SPECIFICATION forming part of Letters Patent No. 687,164, dated November 19, 1901.

Application filed April 20, 1901. Serial No. 56,707. (No model.)

To all whom it may concern:

Be it known that I, EDDY T. MCKAIG, a citizen of the United States, residing in Chicago, in the county of Cook and State of Illinois, 5 have invented a new and useful Improvement in Car-Seats, of which the following is a specification.

This invention relates to the supports of the reversible backs of car-seats of the type 10 in which the back moves from one side of the seat to the other without turning over.

The object of the invention is to provide a simple, strong, durable, and economical construction of the supports which can be easily 15 operated and in the manufacture of which commercial sizes and shapes of flat metal can be largely used.

The nature of the invention will be fully understood from the accompanying drawings, 20 in which—

Figure 1 is an elevation of my improved devices for supporting the reversible back of the car-seat. Fig. 2 shows the same devices in the reversed position from that given in 25 Fig. 1. Fig. 3 is a plan of the parts in the position of Fig. 2, and Fig. 4 is a detail view.

In said drawings, 4 represents the end of the seat-frame, and 5 is an upstanding arm to which the end of the back may be secured 30 and by which it is supported and positioned at the angle desired for the back, the back itself not being shown. The supports other than said arm 5 consist of two main elbow-shaped links 6 and 7, short connecting-links

35 8 and 9, and the pivots uniting said parts to each other and to the seat-frame. Of these the pivot 10 is fixed and passes through the angle of link 6 and the lower end of link 9. The arm 5 has two connections to the fixed 40 pivot, one by means of the long arm of link 6, which is pivoted to the bottom of the arm by pivot 11, and the other by means of the long arm of link 7 and the link 9, the link 7 being pivoted to the arm above its lower end by 45 pivot 12 and the link 9 being joined to the angle of the link 7 by pivot 13. The toes of the two elbow-links are connected together by the link 8, being pivoted thereto by pivots 14 and 15. The two short links are par-

50 allel and retain their parallelism, one of them only shifting somewhat longitudinally dur-

ing changes in the position of the seat-back, and the long arms of the elbow-links also remain substantially parallel, though in moving from one position to the other link 6 moves 55 in front of and from one side to the other of link 7.

The movements of the parts are limited by means of a pin 16, carried by link 9, and the slot 17, formed in a stationary plate 18, attached to the seat and traversed by the pin. 60 This regulates the positions of the seat-back, as will be understood.

While I have shown the mechanism as applied to only one end of the seat and back, it 65 will be understood that duplicate mechanism will be applied to the other end thereof.

In the operation of the seat the link 8 is of great benefit, as it renders the reversing movement steady and even and controls the 70 main links and prevents any independent movement by either of them, so that they cannot lose their proper relative positions. The link 7 has also a lateral extension 19, making it a complete T in form. The edge 75 of the head of this T comes in contact with the top edge of plate 18, and in order that it may not bind on said plate the edge of the T is curved, as shown at 20. This head during a portion of the reversing operation bears 80 at each end on said plate 18, as seen at Fig. 4, and steadies the movement by preventing any wobbling of the mechanism during that time.

I claim—

1. The combination with a back-supporting arm, of two main links supporting said arm and joined to it at separated points one above the other, a pivot supported in a stationary part of the seat-frame and upon which 90 one of said links is pivoted, a connection between the other main link and said pivot, a stop on said connection and a slot on said stationary part engaged by the stop and enabling it to limit the swing of said arm, substantially as specified. 95

2. The combination with a back-supporting arm, of two main links supporting said arm and joined to it at separated points one above the other and also having lateral extensions, a pivot supported in a stationary 100 part of the seat-frame and upon which one

of said links is pivoted, a connection between the other main link and said pivot, and a second short link connecting together said lateral extensions upon the main links, substantially as specified.

3. The combination with the seat-frame of a back-supporting arm, two elbow-shaped main links pivoted to said arm one above the other, a pivot secured to the seat-frame and directly supporting the lower main link, and two short links, one connecting the upper main link to the pivot and the other connecting together the elbow portions of the main links, substantially as specified.

4. The mechanism for supporting the reversible back of a car-seat, having in combination an arm to which the back may be attached, a movable link 7 pivoted at one end to said arm, and supported at its other end by a pivoted link 9, said link 9 and a stationary plate 18 over which said link 7 rides during the reversing operation, substantially as specified.

5. In mechanism for supporting the reversible back of a car-seat, the combination of a back-supporting arm, a link 7 pivotally attached to said arm, and moving with it in the reversing movements and forming one of the supports of the arm, and also having a wide base, and a stationary horizontal surface over which the base of the link moves, substantially as specified.

6. In mechanism for supporting the reversible back of a car-seat, the combination of a back-supporting arm, a link 7 pivotally attached to said arm, and moving with it in the reversing movements and forming one of the supports of the arm, and also having a wide base, and a stationary plate 18 over which the base of the link rides during the intermediate portion of the reversing movement, substantially as specified.

7. In mechanism for supporting the reversible back of a car-seat, the combination with an arm for supporting the back and the mechanism supporting said arm, such mechanism including a link 7 with a wide base, of a stationary controlling-surface over which such base of link 7 rides during the intermediate portion of the reversing movement, substantially as specified.

8. The mechanism for supporting the reversible back of a car-seat, having in combination an arm to which the back may be attached, a movable link 7 made T-shaped at one end and pivoted to said arm at its other end, and also supported by a pivoted link 9, said link 9 and a stationary plate 18 over which said link 7 rides during the reversing operation, substantially as specified.
